UNITED STATES PATENT OFFICE.

JONATHAN EDWARDS WOODBRIDGE, OF DULUTH, MINNESOTA.

PRINTING-TELEGRAPH.

SPECIFICATION forming part of Letters Patent No. 552,738, dated January 7, 1896.

Application filed October 7, 1895. Serial No. 564,910. (No model.)

To all whom it may concern:

Be it known that I, JONATHAN EDWARDS WOODBRIDGE, a resident of Duluth, Minnesota, have invented new and useful Improvements in Printing-Telegraphs, which are fully set forth in the following specification.

The present invention relates to printing-telegraphs, and comprises certain improvements upon the system described and claimed in United States Letters Patent granted to me November 5, 1895, and numbered 549,179; but some of the improvements hereinafter described and claimed may be used in other systems of telegraphy.

15 The transmitter has been simplified by providing a special shift-key to send to line the first impulse which operates the shift-magnet. This key in its normal position causes, say, a plus impulse to go to line, and in its depressed position a minus impulse, the characters of most frequent occurrence being arranged in that row on the type-wheel which is in the printing position when the shift-magnet is traversed by a plus impulse. Consequently only three tilting pole-changing frames are required, one for each stop-magnet, and but twenty-seven, instead of fifty-four, character-keys are required, each key having two characters assigned to it upon a principle common in type-writers.

The printing and paper-feed mechanisms have been simplified and greatly improved in point of rapidity and certainty of action.

Heretofore the printing-shaft was thrown into operation by a clutch operated by the printing-magnet. According to the present invention this shaft is actuated by a spring which is kept wound up by a continuously-rotating motor, the shaft being held normally stationary by the armature of the printing-magnet. When the circuit of the latter is closed the printing-shaft is released, immediately making a revolution, actuating the printing-arm. Said shaft also carries the finger of a "Geneva" stop mechanism, the notched wheel thereof being on the shaft of one of the feed-rolls of the paper-feed mechanism, thus feeding the paper forward one space before the printing-shaft completes its revolution.

In place of the two main-line relays a double relay has been devised having two main-

line coils arranged parallel to each other. The cores of these coils have each a polar projection at each end, as in the Wheatstone 55 relay, and between each pair of polar projections is a tongue or armature, the armatures being independently movable, and in that respect differing from the Wheatstone relay. The relay also has a magnetizing-core 60 and pole-pieces, taking the place of a permanent magnet. In a relay so constructed one armature will respond to positive and the other to negative impulses. The commutator mechanism at the receiving end of the 65 line has also been improved in such manner as to dispense with one of the "three-point" switches, to reduce the number of batteries and to simplify the circuits.

These and other improvements will be more 70 fully understood from the following detailed description, reference being had to the accompanying drawings, in which—

Figure 1 is a diagram illustrating the arrangement of the apparatus and the circuit 75 connections. Fig. 2 is an elevation partly in section showing a portion of the keyboard and pole-changing mechanism of the transmitter. Fig. 3 is a plan view of part of the printing mechanism. Fig. 4 is an end elevation 80 thereof. Figs. 5 and 6 are details in end and side elevation of the double relay.

The construction and operation of the several parts of the system, except as hereinafter pointed out, are or may be the same as described in my aforesaid patent. The transmitter has an ordinary keyboard similar to that of a Remington type-writer.

The pole-changer 70 which determines the direction of the first line-impulse, or that 90 which operates the shift-magnet M, is connected directly with a key U², which may be termed the "shift-key," instead of being connected with and operated by a tilting frame. When so constructed each character-key had 95 to be provided with means for operating the tilting frame of pole-changer 70, since an impulse must always go to line when switch-arm S is on plate 50. By connecting the pole-changer 70 directly with a special key one of 100 the tilting frames and its actuating devices can be dispensed with, leaving only three frames T' T² T³, Fig. 2.

Each key-lever U has, as before, two up-

rights U' , provided with projections w for operating the tilting frames. Moreover the number of keys is reduced to half, it not being necessary to provide a separate key for each character as before. Each key can by this arrangement have two characters assigned to it, the pair of characters being those occupying corresponding positions in the two rows of type on the type-wheel.

- 10 As shown the contact-plate of pole-changer 70 normally connects the line-terminal 60 with the plate 54 connected with the positive pole of main battery MB, so that the first line-impulse, when the key is in its usual position, 15 will be positive. At the receiving end the letters of the alphabet with the character "&" may be arranged in one row, on type-wheel A, and the figures, punctuation-marks and characters less frequently used in the other. The 20 first row will be in the printing position when the shift-magnet M has responded to a positive impulse. Hence in transmitting, the shift-key is only used for characters in the second row of type.
- 25 The other pole-changers 71 72 73, which respectively control the stop-magnets $M' M^2 M^3$, normally rest as before on an insulating-strip 57 between the positive and negative terminal plates 54 55 of the main battery. The terminal plates 61 62 63 are connected respectively with the commutator-plates 51 52 53 and the center of the main battery is connected to ground, as before, by a wire 56.

Referring to the apparatus at the receiving 35 end of the line, shaft B of printing-wheel A has a sleeve B' loose thereon, and on the latter is the pulley b held by frictional contact (due to the pressure of spring c') between collars c^2 on said sleeve. The pressure of spring 40 c' can be adjusted by a nut a^2 . Arm B^2 fast on sleeve B' is attached at one end to spiral spring c, which is the driving-spring, the other end of the latter being attached to shaft B. Pulley b is continuously rotated by a cord, as 45 heretofore, keeping spring c wound up, the pulley slipping against the pressure of its frictional holding devices when spring c is at its utmost tension. Printing-shaft f also carries a constantly - driven pulley f^2 , loose 50 thereon, but connected with the shaft by the frictional contact of collars f^3 maintained by spring f^4 , adjustable by means of a nut f^5 . This shaft carries a finger G, which normally 55 engages the hooked end of one branch of the forked armature m^4 of printing-magnet M^4 . Obviously when the armature m^4 is in its normal position pulley f^2 rotates idly, but when the armature is attracted by its magnet, which occurs as soon as the type-wheel 60 has turned to its printing position, shaft F is released and makes a complete revolution, during the first part of which an eccentric thereon actuates printing-lever N, causing the printing-roller n^7 on the end thereof to press 65 the paper against the type. Shaft F also carries the finger o of a "Geneva" stop mechanism, the notched wheel P thereof being on a

short shaft o', which carries a serrated feed-roller o². The paper strip passes, as indicated, between this roller and a companion roller o³, 70 carried on the end of an arm P². Consequently during the last part of the revolution of shaft F the paper is fed forward one step. During this part of the revolution also, finger G makes contact with the other branch m^6 of 75 the forked armature, restoring it positively, but it may be restored by a spring m⁷. G² represents an inking-roller.

The double relay which is to take the place of the two relays has the two main-line coils 80 R R' and the magnetizing-coil R². At one end of the coils R R' is the positive armature r and at the other the negative armature r' . These armatures are, for the purposes of this invention, biased in opposite directions. 85 Each armature is between pole-pieces $r^2 r^3$, which are extensions of the cores of the line-coils R R', and each is magnetized by a polar projection r^4 or r^5 of the core of the magnetizing-coil. The armatures are separately pivoted so as to act independently, this being 90 the chief structural difference between this relay and the Wheatstone relay. Obviously this relay will perform all the functions of two Wheatstone or other polarized relays in 95 a system such as described, or in other systems where two relays are required. The connections of the relay could be reversed, using coil R² as the line-coil and coils R R' as magnetizing-coils.

Referring to the diagram Fig. 1 the principal change is in the construction of the main and auxiliary commutators. The main commutator, which controls the circuit of the shift-magnet M and stop-magnets $M' M^2 M^3$, 105 through local battery LB, has eight contact-plates, instead of four, and the auxiliary commutator has sixteen plates instead of eight. For each character the switch-arms $s s'$ of the main and auxiliary commutators make half 110 a revolution, the contact-plates of each being duplicated or composed of two series, the corresponding plates of each series being electrically connected, as shown. Thus plate 10 of the main commutator is connected by a wire 115 to plate 10^a, both being in the circuit of shift-magnet M, plate 11 is connected to 11^a, and both to stop-magnet M' , and so on. Escapement-magnet M^5 and its mechanism are the same as before in construction and operation. 120 This magnet, through lever p' and escapement-wheel p, permits a step-by-step movement in a well-known manner to the shaft p^2 , on which the switch-arms $s s'$ are mounted. Switch-arm s' of the auxiliary commutator 125 normally rests on plate v, but at the first movement of the shaft it passes to plate v', which, as heretofore, sends a current from a local battery LB' through the escapement-magnet M^5 , reversing the movement of lever 130 p' and permitting shaft p^2 to move another step.

It will be observed that plate v' and every alternate plate v³ v⁵, &c., until we reach the

plate v^a , directly opposite the starting-plate v , are connected together and to wire 28, leading to the back-stop of armature r , while the plates $v^2 v^4$, &c., are connected in like manner to the wire 26, leading to the back-stop of armature r' . Switch-arm s' is itself connected by a wire 50 to one side of battery LB'. Hence the circuit, when the switch-arm is on plate v' , is from battery LB' by wire 50 to the switch-arm s' , to plate v' , wire 28, armature r , wire 17, through escapement-magnet M^5 to the other side of battery LB'.

key-levers, one of said pole-changers being connected directly with a key-lever, and actuating mechanism for shifting the other pole-changers; each key-lever, except that connected directly with a pole-changer, being arranged to control a different combination of pole-changers, substantially as described.

2. In a printing telegraph system having at the receiving station a type-wheel with the type arranged in two parallel rows, a magnet for shifting the type-wheel, and electro-magnetic mechanism for causing the type-wheel to rotate to and assume different axial positions, the combination of a commutator and pole-changers at the transmitting station for sending to line negative and positive impulses, a shift-key connected directly with one of said pole-changers, character keys and intermediate mechanism for setting the other pole-changers, substantially as described.

3. The combination with the printing shaft and the type-wheel of a constantly driven pulley having a frictional connection with said shaft, an armature normally holding said shaft stationary, a printing lever and paper feed mechanism actuated by the rotation of said shaft, substantially as described.

4. In a printing telegraph receiver, the combination with the type-wheel, of a printing shaft, a constantly driven pulley thereon frictionally connected with said shaft, a printing magnet, an armature normally engaging and holding a finger on said shaft, said armature having a branch with which said finger makes contact before completing a revolution, thereby restoring said armature positively, paper feed-mechanism, and a printing lever actuated by the movement of said shaft, substantially as described.

5. The combination with a type-wheel or impression device, of a printing shaft and means for rotating it intermittently, paper feed rolls, and a Geneva-stop mechanism for actuating said rolls, operated by said shaft, substantially as described.

6. The combination with a type-wheel, of a printing shaft and means for rotating it intermittently, a printing lever operated by said shaft during its revolution, paper feed-rolls, and a Geneva-stop mechanism, for actuating said rolls operated by said shaft after the printing lever has made its stroke, substantially as described.

7. The combination with the type-wheel, the printing-shaft and means for rotating the printing shaft, of paper feed mechanism comprising a Geneva-stop, the finger being actuated by said shaft, and the notched-wheel being connected with the paper feed rolls, substantially as described.

8. In a telegraph receiver, the combination of the distributing commutator controlling the circuits of a local battery, and having two series of contact plates, escapement mechanism for actuating the switch-arm of the commutator, an auxiliary commutator having two

15 20 25 30 35 40 45 50 55 60 65 70 75 80 85 90 95 100 105 110 115 120 125 130

plate v^a for controlling the circuit of printing-magnet M^4 . As shown, plate v is connected by wire 40 to one terminal 38 of a three-point switch, and wire 41 leads to the other terminal 39, the movable arm q^4 thereof being controlled, as heretofore, by the printing-shaft. The plates v v^a and arm s' therefore constitute a three-point switch, replacing the separate three-point switch heretofore used. Arm q^4 is, as shown, resting upon terminal 39, and the circuit of printing-magnet M^4 is consequently open until arm s' reaches plate v^a , which will occur when arm s has reached plate 10^a , having set all the stop-magnets. At this time the circuit of magnet M^4 is closed through local battery LB', as is obvious from the diagram. The printing-shaft then rotates, performing the operations heretofore described, and also transferring arm q^4 to terminal 38, so that the circuit of magnet M^4 will again be closed when arm s' reaches resting-plate v . Battery LB' is thus used both to operate the printing-magnet M^4 and also to energize the escapement-magnet M^5 to throw back the lever p and to work it forward in the absence of a line-impulse.

Except as herein pointed out, the system is constructed and operated as described in my above-mentioned patent. The stop-magnets $M' M^2 M^3$ are designed to operate singly or in various combinations, to determine the position of a stop capable of arresting the type-wheel A at any one of its printing positions, the armature of each stop-magnet having three functional positions, one of which is determined by a positive line-impulse, one by a negative line-impulse, and one by the omission of the corresponding impulse. As this stop mechanism is fully described in my patent aforesaid and forms no part of the present invention I have not shown it in the drawings accompanying this specification. Furthermore, it is evident that the improvements herein described, or many of them, may be used in various known systems of printing-telegraphs and other telegraph systems.

Having now fully described my invention, what I claim as new, and desire to secure by Letters Patent, is—

65 1. In the transmitter the combination of the commutator, the series of pole-changers, the

series of contact plates connected in circuit with the escapement magnet, and two resting plates, a printing magnet, and a three-point switch having its stationary terminals connected respectively with said resting plates, and its movable part with said printing magnet, substantially as described.

In testimony whereof I have signed this specification in the presence of two subscribing witnesses.

JONATHAN EDWARDS WOODBRIDGE.
